UNITED STATES PATENT OFFICE.

MILO C. NEWTON AND JOSEPH A. GREMLING, OF DELPHOS, OHIO, ASSIGNORS TO THE
E. & N. MANUFACTURING COMPANY, OF DELPHOS, OHIO, A CORPORATION OF OHIO.

BROOM.

Application filed October 22, 1927. Serial No. 227,928.

This invention relates to brooms and has for its object to provide a broom which is simple in construction, durable and inexpensive to manufacture.

More specifically, it is an important object of the invention to provide a broom in which all binding of the bristles below the supporting head is dispensed with and in which a circumferential cushioning means is provided in connection with the head, which yieldingly resists the spreading of the bristles and causes the bristles to bend when the broom is in use along extended and gradual curves so that the breaking of bristles due to sharp bends therein is minimized.

A further object is to provide a fabric cushioning band for the bristle body which also serves as a shock absorbing covering for the supporting head, which takes the force of the impact when the head is struck against a solid object such as a piece of furniture and protects the head against damage and prevents marring of the furniture.

With the above and other objects in view, the invention may be said to comprise the device as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification, in which Figure 1 is a side elevation of a broom embodying the invention.

Fig. 2 is a side elevation on an enlarged scale of the brush portion of the broom, with part of the brush supporting structure broken away and shown in section.

Fig. 3 is a section taken on the line indicated at 3—3 in Fig. 2.

Fig. 4 is a section taken on the line indicated at 4—4 in Fig. 2.

Fig. 5 is a section taken on the line indicated at 5—5 in Fig. 2.

Fig. 6 is a fragmentary sectional perspective view showing the head with a sheet metal retaining band thereon.

Fig. 7 is a sectional perspective view of the cushioning band detached from the head.

Referring to the accompanying drawings, the broom of the present invention is provided with a transversely elongated brush supporting head 1 in the form of a block,

which has the usual broom handle 2 attached in a central socket 3, which extends downwardly from the upper edge of the block, the handle being retained in the socket by suitable transverse fasteners such as nails 4. A brush holding socket is provided beneath the block 1 by means of a sheet metal retaining band 5 which encircles the block and projects downwardly from the lower edge thereof, the upper edge of the band 5 being secured to the block 1 by means of suitable fasteners such as nails 6. The brush is in the form of a body of bristles 7 which have their upper ends glued together into a solid mass of a form corresponding to that of the socket 8 formed by the projecting band 5, but somewhat smaller than the socket formed by the band 5. The bristles are preferably glued together in a suitable form prior to the attachment of the body of bristles to the head 9 and the glued ends of the bristles may be enclosed in a thin band 9 of paper or other suitable material to protect the glued ends in the interval between the gluing operation and the assembly in the head.

A cushioning band 10 encircles the retaining band 5 and is interposed between the body of bristles and the inner wall of the band 5. This band extends above the upper edge of the sheet metal band 5 and is attached to the block 1 along its upper edge by suitable fastening means such as nails 11. The band 10 is preferably formed of a piece of relatively thick soft fabric such as felt, of a width considerably greater than the width of the band 5 and the lower portion of the band 10 is turned inwardly upon the interior of the band 5 and substantially covers the inner wall of the band 5 from the lower edge thereof to the lower edge of the block 1. The inturned portion 12 of the band 10 is interposed between the upper end of the brush body and the band 5, and the glued upper end 8 of the brush body is of a size such that it has a tight fit within the inturned portion 12 of the cushioning band.

The socket formed by the sheet metal band 5 and fabric band 10 is of a depth in excess of the depth of the glued portion 8 of the brush body and the thick fabric 10 provides a rounded edge 13 at the open edge of the socket over which the bristles bend when the broom is in use. The brush body is retained within the socket of the head by means of transverse retaining members 14, which may be in the form of nails extending through the opposite sides

of the band 5 adjacent the lower edge of the band, through the inturned portions of the fabric band 10 and through the body of bristles, the nails 14 being clenched upon the band 5 at one side thereof.

In the manufacture of the broom, the sheet metal band is first applied to the block 1 and the portion 12 of the fabric band 10 is then inserted upon the interior of the band 5. The 10 glued portion 8 of the brush body 7 is then forced into the socket within the portion 12 of the cushioning band. The brush retaining nails 14 are then driven through the band 5, the inturned portion of the cushioning band 15 and the bristles 7 and clenched. The cushioning band 10 is then turned upwardly over the outside of the sheet metal band 5 and secured to the block 1 by the nails 11.

By reason of the fact that the glued portion 20 8 of the brush body terminates above the open end of the retaining socket, lateral movements of the unattached bristles immediately below the glued portion is limited by the yieldable fabric wall 12 so that when the broom is in use, the pressure of the bristles will not create a sharp bend on the bristles at the lower edge of the glued portion, but will produce a gradual bend from the glued portion to the rounded edge 14. If a heavy downward pressure is 30 exerted on the brush body in sweeping the broom, no sharp bends will be produced in the individual bristles since the bristles are forced to bend gradually from their glued portions and then over the rounded edge 14 which is of 35 sufficiently large radius to prevent bending of the bristles to their breaking point.

The cushioning band 10 in addition to providing a cushion for the bristles, also provides an impact cushioning cover for the head, which protects the head against damage by impact against solid objects and prevents marring of furniture when the head strikes against the furniture in sweeping.

What we claim is:

45 1. A broom comprising a supporting block having a handle extending from the upper portion thereof and a brush receiving socket, a brush composed of a body of bristles bound together at their upper ends only, the bound portion being in the form of a solid mass of a shape corresponding to that of the socket and of less depth than the socket, a cushioning band of relatively thick pliable fabric interposed between said body of bristles and the wall of said socket, and means for securing said brush and band within the socket with the fabric extending in the socket below said bound portion of the brush to yieldingly restrain lateral movements of the bristles and 60 prevent formation of sharp bends in the bristles.

2. A broom comprising an elongated supporting block having a handle secured thereto and an elongated brush receiving socket 65 along the lower edge thereof, a brush com-

posed of a body of bristles bound together at their upper ends only, the bound portion being in the form of a solid mass of a shape corresponding to that of the socket and of less depth than the socket, a cushioning band of felt closely encircling the upper end of said body of bristles and closely fitting within the socket, said band extending in the socket below the bound portion of the brush and outwardly around the edge of the socket to form a rounded yielding edge over which the bristles may be flexed.

3. A broom comprising an elongated supporting block having a handle secured thereto and an elongated brush receiving socket along the lower edge thereof, a brush composed of a body of bristles having their upper ends bound together in a solid mass of a shape corresponding to that of the socket, a cushioning band of felt closely encircling the upper end of said body of bristles and closely fitting within the socket, said band extending outwardly around the edge of the socket to form a rounded yielding edge over which the bristles may be flexed, and transverse fastening members extending through the felt-band and body of bristles within the socket for retaining the same in the socket.

4. A broom comprising a supporting block having a handle attached thereto, a brush composed of a body of bristles having their upper ends bound together in a solid mass and positioned adjacent the lower edge of said block, and means for securing said body of bristles to said block comprising a retaining band encircling the block and the upper portion of the body of bristles, a cushioning band encircling the retaining band and having its lower edge turned back within the stiffening band between the same and the body of bristles and means for securing said bands to the block and to said body of bristles.

5. A broom comprising a supporting block having a handle attached thereto, a brush composed of a body of bristles having their upper ends bound together in a solid mass and positioned adjacent the lower edge of said block, and means for securing said body of bristles to said block comprising a sheet metal band encircling the lower portion of the block and the upper portion of the body of bristles, a felt band covering the sheet metal band and turned back upon itself within the lower portion of the sheet metal band adjacent to the lower edge of the block, the upper portion of the body of bristles having a close fit within the inturned portion of the felt band, means for fastening the upper portions of said bands to said block, and fastening members passing through said bands and said body of bristles.

6. A broom comprising a supporting block having a handle attached thereto, a sheet metal band encircling said block and secured thereto, said band projecting below the lower edge of said block to form a brush receiving

socket, a relatively thick fabric band encircling the block and sheet metal band and secured to the block, said fabric band being turned back upon itself around the lower edge 5 of said sheet metal band, and a brush composed of a body of bristles having their upper ends glued together in a solid mass of a shape to fit closely within the inturned position of said fabric band, the glued portion of 10 said fabric band, the glued portion of the bristles terminating short of the open end of said socket.

7. A broom comprising an elongated supporting block having a handle projecting from the upper edge thereof, a sheet metal 15 band encircling said block and projecting below the lower edge thereof, fastening means securing said band along its upper edge to said block, a band of felt encircling said sheet metal band and block, said felt band having

its upper edge above the upper edge of the 20 sheet metal band and its lower portion turned inwardly against the inner side of the projecting portion of the sheet metal band and extending substantially to the lower edge of the block, and a body of bristles having their 25 upper ends glued together in a solid mass of a shape to fit closely within the inturned portion of said fabric band, the glued portions of the bristles terminating short of the open 30 end of the socket, and fastening members extending through the opposite walls of the sheet metal band, the inturned portion of the felt band and the body of bristles.

In testimony whereof we affix our signatures.

MILO C. NEWTON.

JOSEPH A. GREMLING.
